UNITED STATES PATENT OFFICE.

JAMES G. CLARK AND LOUIS F. MEHDER, OF OSHKOSH, WISCONSIN.

POCKET.

No. 825,189.

Specification of Letters Patent.

Patented July 3, 1906.

Application filed July 27, 1905. Serial No. 271,516.

To all whom it may concern:

Be it known that we, JAMES G. CLARK and LOUIS F. MEHDER, citizens of the United States, residing at Oshkosh, in the county of Winnebago and State of Wisconsin, have invented new and useful Improvements in Pockets, of which the following is a specification.

Our invention relates to pockets for garments, and especially to those which are sewed upon the exterior, as upon overalls, jackets, and shirts, such as are sometimes called "patch-pockets."

Our invention relates to a side-entrance watch-pocket, the object being to provide a safety-pocket. A workingman often throws his jacket down hastily and hastily picks it up by taking hold of any part of the garment. With our invention the watch will not spill in any position, and yet may be withdrawn by the chain.

Our invention also provides a pencil-pocket in combination with the watch-pocket, both pockets being formed by the same patch.

In the accompanying drawings, Figure 1 represents an outside front view of our invention. Fig. 2 is a vertical section on the line A B, and Fig. 3 is a horizontal section on the line x x.

Referring to the drawings by numerals, 2 represents the garment, and 3 represents the patch, which is usually stitched around the edges to the garment by two rows of stitches 4 to 4 to form the pocket. The pocket is closed at the top, except at the top of pencil-pocket 5, which is open for insertion of the pencil 6. A side opening 7 is provided near the center of the front side of the pocket for admission 40 of the watch 8, secured to a buttonhole of the garment (not shown), by the chain 9. Inwardly-extending points 10 and 11 are provided by stitching the patch to the garment with one or more rows of stitches 12 12' and 13 13', thus closing off a portion of the pocket above and below the opening and forming a diagonal inwardly-extending barrier to pre-

vent the watch from falling through the opening 7. Each set of stitching is formed in the shape of a triangle. The angle of the upper point 10 is preferably made more acute than the angle of the lower point 11, as shown in Fig. 1. If the garment is held bottom upward or at any inverted angle, the watch will drop into the top of the pocket and egress be prevented by the incline 12' and the point 10. When the workman stoops forward, the watch will shift and bear against the incline 13', and thereby be prevented from falling through the opening 7. The watch may, however, at any time be removed by means of the chain 9.

Cross-stitches are provided at 14 to form the bottom of the pencil-pocket.

Having thus described our invention, what we claim is—

1. In a garment, the combination with a patch suitably secured thereto, producing a pocket, said pocket having a side opening, of an upper and a lower triangular set of stitches 70 extending inwardly only from the side provided with said opening, said sets of stitches producing a pointed structure and leaving the entire ends and opposite side of the pocket free, said triangular sets of stitches 75 overhanging portions of the upper and lower ends, the upper set of stitches being formed at a more acute angle than the lower set.

2. In a garment, a pocket provided with a vertical side having an entrance through said 80 side contracting in width toward the interior of the pocket, and with receptacles formed above and below the entrance.

3. In a garment, a pocket provided with a side entrance thereto, and expanding in 85 width above and below the said entrance.

In testimony whereof we affix our signatures in presence of two subscribing witnesses.

JAMES G. CLARK.
LOUIS F. MEHDER.
